UNITED STATES PATENT OFFICE

ALWIN G. STEINMAYER, OF MILWAUKEE, AND WILLIAM E. KRUEGER, OF SOUTH MILWAUKEE, WISCONSIN, ASSIGNORS TO LINE MATERIAL COMPANY, OF SOUTH MILWAUKEE, WISCONSIN, A CORPORATION OF DELAWARE

SWITCH

Application filed September 12, 1929. Serial No. 392,128.

This invention relates to certain new and useful improvements in switches and refers more particularly to a switch adapted for use with electric flush valves.

5 Valves of this nature are usually operated by a solenoid which requires but momentary energization to effect the opening of the valve, and heretofore the switches controlling the solenoid circuit, which are usually actuated by a push button, have been of such construction that the solenoid would remain energized, and the water would continue to flow through the valve, as long as the push button was held in. For obvious reasons this 10 construction was extremely objectionable, and therefore, it is an object of this invention to provide a switch by which a circuit may be maintained closed for a predetermined time only, irrespective of the position of the 15 button.

Another object of this invention resides in the provision of a switch of the character described which makes it necessary to release the push button actuator before the circuit 20 can be again closed.

A more specific object of this invention resides in the provision of spaced stationary contacts adapted to be bridged by a movable contactor which is moved to contact making 25 position by depressing a push button and which is returned to normal inoperative position irrespective of the position of the push button actuator.

And a further object of this invention resides in the provision of a switch of the character described having means for retarding the return of the contactor to circuit breaking 30 position.

With the above and other objects in view 35 which will appear as the description proceeds, our invention resides in the novel construction, combination and arrangement of parts substantially as hereinafter described and more particularly defined by the appended claims, it being understood that such changes in the precise embodiment of the hereindisclosed invention may be made as come within the scope of the claims.

In the accompanying drawings, we have 40 illustrated one complete example of the phys-

ical embodiment of our invention constructed according to the best mode we have so far devised for the practical application of the principles thereof, and in which:

Figure 1 is a top view of a switch structure embodying our invention. 55

Figure 2 is a side elevational view with a portion thereof broken away to illustrate structural details.

Figure 3 is a transverse sectional view 60 taken through Figure 1 on the plane of the line 3—3; and

Fig. 4 is a cross sectional view taken 65 through Figure 1 on the plane of the line 4—4.

Referring now more particularly to the accompanying drawings in which like numerals designate like parts throughout the several views, the numeral 5 represents a base 70 preferably formed of porcelain or other suitable insulating material, hollow at its bottom and provided with an upwardly extending boss 6 adjacent one end.

Mounted on the upper face of the boss 6 is a pair of stationary spaced contacts 7 and 8 which are secured in position by terminals 9 and 10 fixed to the base by studs 11 passed through suitable apertures to receive nuts 12 at their lower ends. The terminals 9 and 10 are adapted to have conductors 13 and 14 75 connected therewith which lead to the circuit 80 adapted to be closed by the switch, and are electrically bridged to close the circuit upon engagement of a movable contactor 15 with spring fingers 16 and 17 projected from the 85 contacts 7 and 8 respectively.

The contactor 15 is movably mounted in a manner to be later described and engages the spring fingers 16 and 17 to electrically bridge them upon depression of a push button 18. 90 The means for mounting and guiding the movement of the contactor comprises a channel shaped frame 19 fixed centrally to the top of the base 5 by screws 20, its vertical sides 21 being cut away as at 22 at their ends adjacent the boss 6. The cut away portions 22 have substantially vertical rear walls 23 and inclined forward walls 24.

The contactor 15 consists of a transverse rod 25 having an enlarged central portion 26, 100

and normally rests upon the horizontal bottom 27 of the cut away portions 22 in the vertical sides of the stationary frame 19. A pair of contractile springs 28 maintains the 5 contactor 15 in normal circuit breaking position with the opposite ends of its rod 25 resting on the bottoms 27 of the cut away portions at the juncture of the rear walls 23 thereof, one end of the springs 28 being connected with the extreme outer ends of the rod 25 and their other ends being connected with a fixed transverse rod 29 mounted in aligned apertures in the vertical sides 21 of the stationary frame.

15 The movement of the push button 19 is imparted to the contactor 15 through a substantially U shaped movable frame 30 slidably between the vertical sides of the stationary frame 19 and guided in its movement by the 20 transverse rod 29 passing through an elongated aperture 31 in the sides 32 of the U shaped movable frame and extending through the closed end 33 thereof, and by having the outermost ends of its sides 32 provided with 25 outstruck tongues 34 which engage in elongated apertures 35 in the vertical sides of the stationary frame beneath the cut away portions 22. The push button 18 is connected with the frame 30 by a stud 36 threaded in a 30 suitable aperture in the end 33 of the frame where it is secured by a lock nut 37.

The stud 36, prior to being engaged with a frame 30, also slidably passes through an aperture in the vertical leg of an angle bracket 38 fixed to the base by a screw 39, and an expansive spring 40 is confined between the bracket and the button 18 to normally yieldably maintain the button and the frame 30 in inoperative position.

40 The upper edges of the forward portion of the frame 30 are stepped as at 41 and its extreme forward edges 42 engage in back of the rod 25 of the contactor when the parts are in normal inoperative position, whereby 45 depression of the button 18 and the consequent forward movement of the frame 30 moves the contactor forward along the horizontal bottom of the cut away portions 22. Continued movement of the frame 30 by the 50 button 18 causes the contactor to ride up on the inclined edges of the cut away portions into engagement with the spring fingers 16 and 17 to thus electrically bridge them.

As the movement of the frame 30 is completed, and the contactor rides up on the inclined edges 24 it also moves upwardly along the extreme forward edges 42 of the frame 30 until the axis of the contactor is above the plane of the cut away portions 41 at 60 which time the springs 28 draw the contactor rearwardly and out of engagement with the spring fingers 16 and 17. If the button 18 is maintained in its depressed position the rod 25 of the contactor follows along the top 65 edge of the stepped portion 41 of the frame

until it engages the vertical rear walls 23 of the cut away portions 22 in the main frame at which time it will be disengaged from the adjacent ends of the spring fingers.

To retard the return of the contactor to normal circuit breaking position by the action of the springs 28 sufficiently long to maintain the circuit closed for the desired length of time, a dash pot structure is incorporated, which includes a cylinder 43 having a central web 44 extended from its closed end to be connected with the enlarged portion 26 of the contactor. Cooperating with the cylinder 43 is a piston 45 from the outer end of which a lug 46 extends to pivotally connect the piston with the stationary transverse rod 29. The closeness of the fit of the piston in the cylinder determines the effectiveness of the dash pot and thus governs the time required to return the contactor to normal circuit breaking position.

From the foregoing description taken in connection with the accompanying drawings it will be readily apparent to those skilled in the art to which our invention appertains that we provide a novel switch which is particularly adapted to electric flush valves and the like as it opens its circuit independent of the push button actuator making it impossible to maintain the solenoid circuit closed by holding the push button "in".

What we claim as our invention is:

1. In a switch of the character described, a stationary contact, a contactor movable to engagement with the stationary contact, means for guiding the movement of the contactor, an actuator for moving the contactor, means whereby the guide means for the contactor breaks the operative connection between the contactor and the actuator, and means for moving the contactor out of engagement with the stationary contact upon breaking of the operative connection between the actuator and the contactor irrespective of the position of the actuator.

2. In a switch of the character described, a stationary contact, a movable contactor engageable with the stationary contact, guide means for guiding the movement of the contactor, yieldable means normally maintaining the contactor in inoperative position, and an actuator operatively connected with the contactor for moving the same along its guide means into engagement with the stationary contact, said guide means being arranged to break the operative connection between the actuator and the contactor after the contactor is engaged with the stationary contact, whereby the yieldable means is free to return the contactor to its normal inoperative position independent of the position of the actuator.

3. In a switch of the character described, a stationary contact, a contactor movable into engagement with the stationary contact, a

- frame forming a guide-way for the movement of the contactor, means yieldably tending to maintain the contactor in inoperative position at all times, an actuator movable in the frame and engageable with the contactor to move the same along said guide-way to engagement with the stationary contact, and said actuator being so formed as to become disengaged from the contactor after initial engagement of the contactor with the stationary contact, to release the energy of the means tending to maintain the contactor in inoperative position whereby the contactor is disengaged from the stationary contact irrespective of the position of the actuator.
4. In a switch of the character described, a stationary contact, a movable contactor engageable with the stationary contact, means for guiding the movement of the contactor and including an incline, means normally yieldably tending to maintain the contactor at the bottom of the incline, an actuator for pushing the contactor upwardly along the incline to engagement with the stationary contact, and the actuator being of such construction that the movement of the contactor along the incline disengages the contactor from the actuator and releases the energy of the yielding means, whereby the contactor is moved out of engagement with the stationary contact independent of the position of the actuator.
5. In an electric switch including a stationary contact and a movable contactor engageable therewith, an actuator, an abutment carried by said actuator and engageable with a contactor carried part to transmit movement of the actuator to the contactor, means for guiding the movable contactor into engagement with the stationary contact, and means for yieldably urging the contactor out of engagement with the stationary contact, said guiding means moving the contactor carried part out of engagement with the abutment to free the contactor for movement out of engagement with the stationary contact by said yieldable means.
6. In an electric switch of the character described, a stationary frame having spaced walls, a stationary contact, a movable contactor engageable with the stationary contact, an actuator movable between the spaced walls, an abutment on the actuator and engageable with a contactor carried part for transmitting movement of the actuator to the contactor, inclined guide means carried by the walls for guiding the contactor into engagement with the stationary contact, the top of said abutment being in a plane beneath the plane of the top of the inclined guide means whereby the contactor carried part becomes disengaged from the abutment as the contactor rides up the inclined guide means into engagement with the stationary

contact, and means for moving the contactor out of engagement with the stationary contact upon disengagement of its part from the abutment.

In testimony whereof we have hereunto affixed our signatures.

ALWIN G. STEINMAYER.
